CLAIM

The ornamental design for a container for cosmetics, as shown and described.

DESCRIPTION

FIG. 1 is a top front perspective view of the container for cosmetics according to the present invention;

FIG. 2 is a bottom rear perspective view thereof;

FIG. 3 is a top view thereof;

FIG. 4 is a top front perspective view thereof with the lid raised;

FIG. 5 is a bottom rear perspective view thereof;

FIG. 6 is a front view thereof;

FIG. 7 is a rear view thereof;

FIG. 8 is a left side view thereof;

FIG. 9 is a right view thereof;

FIG. 10 is a top front perspective view thereof with the lid arranged upside down; and,

FIG. 11 is a bottom view thereof.

The broken lines shown in the figures that are immediately adjacent to the shaded areas and define unshaded regions represent the bounds of the claim. All other broken lines, including the features within broken line boundaries, are directed to environment. The broken lines form no part of the claimed design.
